FIG. 2

UNITED STATES PATENT OFFICE

2,639,085

VACUUM PUMP

Merriam E. Johnson, Rochester, N. Y., assignor to
 Eastman Kodak Company, Rochester, N. Y., a
 corporation of New Jersey

Application January 2, 1951, Serial No. 203,946

3 Claims. (Cl. 230—101)

1

This invention relates to vacuum pumps and is particularly concerned with vertical diffusion pumps of the fractionating type.

One type of pump commonly employed for producing high vacuum is the vertical concentric diffusion pump. This pump is characterized by having a generally cylindrical vertical pump casing with a plurality of concentric vapor chimneys disposed in the casing and generally concentric with the casing. The vapor chimneys are rigidly secured to each other and have their lower ends extending to the bottom of the pump casing to form a plurality of concentric boiler compartments, and the vapor chimneys terminate upwardly in jet nozzles from which pumping vapors emerge to exert their pumping action in the pump casing. The boiler compartments are interconnected in series by an aperture in the lower end of each chimney whereby pump fluid flows through the compartments in turn and is fractionated so that the lowest vapor pressure components exert their pumping action from the jet nozzle nearest the high vacuum inlet and the higher vapor pressure components exert their pumping action from jet nozzles successively closer to the high pressure outlet of the pump. Such pumps are well known in the art as shown in Malter U. S. Patent 2,112,037; Hickman U. S. Patent 2,206,093 and Hickman 2,211,329.

In order for such pumps to function most effectively, it is necessary that the various boiler compartments be isolated except for a single fluid pathway, which is preferably a tortuous pathway, whereby the pump fluid can be fractionated during travel. Thus, seepage from one boiler compartment to another under the lower ends of the chimneys, due to unevenness in the bottom of the casing or slight differences in the alignment of the lower ends of the chimneys, introduces high vapor pressure constituents into zones wherein only lower vapor pressure constituents should be vaporized. This results in an impairment of the efficiency of the pump, as regards both the ultimate vacuum attained and the pumping speed.

Various expedients have been proposed to solve the seepage problem. The chimneys can be welded to the bottom of the casing but the resulting pump cannot be disassembled for cleaning or repairs. Baffles have been welded to the bottom of the pump casing into which the vapor chimneys fit. This is a costly and time consuming operation, however, and makes the pumps difficult to clean. The bottom of the casing and the ends of the chimneys have been carefully machined and the concentric chimneys carefully se-

2

cured together in exact alignment to insure a tight fit between the bottom of the casing and the lower ends of all of the chimneys. This is also a costly expedient, and the resulting apparatus is subject to impairment by slight warpage of the elements. Grooves have been machined into the bottom of the casing to receive the chimney ends. This is also a costly procedure, and pump fluid tends to char in the grooves which are difficult to clean. The chimneys have been capped, which effectively prevents seepage but renders cleaning of the chimneys more difficult.

It is accordingly an object of this invention to provide an improved vertical fractionating diffusion pump.

Another object of the invention is to provide novel and effective means for minimizing seepage of pump fluid in a vertical diffusion pump.

Another object of the invention is to provide a simple diffusion pump which is readily assembled and disassembled and which has improved performance characteristics.

Another object of the invention is to provide means for improving the ultimate vacuum and pumping speed of a conventional diffusion pump without necessitating radical changes in structure.

Other objects will be apparent from the description and claims which follow.

These and other objects are attained by means of this invention as described more fully hereinafter with reference to certain preferred embodiments as illustrated by the drawings.

Of the drawings:

Fig. 1 is a view in elevation, partly broken away and in section, of a vertical diffusion pump constituting a preferred embodiment of the invention; and

Fig. 2 is a partial section taken on line 2—2 of Fig. 1.

With particular reference to the drawings, the illustrated pump embodying the invention comprises the combination with a vertical diffusion pump of the type including a generally cylindrical pump casing 10 having disposed therein and generally concentric therewith vapor chimneys 11, 12 and 13 which are arranged with the lower ends of the chimneys resting on the bottom 14 of casing 10 to form concentric boiler compartments 15, 16 and 17, of means for preventing seepage of pump fluid between the boiler compartments as described more fully hereinafter.

Pump casing 10 is provided with a flanged high vacuum inlet port 18 adapted to be attached to a system to be evacuated, and a flanged high pres-

sure outlet 19 adapted to be connected to a back-ing pump. A heater element 20 is secured to the bottom 14 of casing 10. The vapor chimneys 11, 12 and 13 terminate upwardly in jet nozzles, one of which is shown in detail at 21. Chimneys 11, 12 and 13 are rigidly held in spaced-apart relation by spacer brackets 22, 22.

Each chimney is singly notched at its lower end, the notches 23, 23 being spaced so that the notch in one chimney is spaced approximately 180° from the notches in the next adjacent chim-neys.

The means for minimizing seepage between the boiler compartments comprises floating col-lars 24, 25 and 26 cooperating respectively with chimneys 11, 12 and 13. Each collar is disposed closely adjacent to and generally concentric with the lower end of one of the chimneys, the collar being sufficiently larger or smaller than the closely adjacent chimney to permit the collar to move vertically relative to the chimney. Preferably the collars are of such diameter as to be out of circumferential contact with the chimneys. Each collar is provided with a single notch in its lower edge as indicated at 27, with the notch 27 prefer-ably being in general alignment with the notch 23 in the closely adjacent chimney to permit passage of pump fluid through the boiler com-partments.

The collars 24, 25 and 26 extend upwardly along the chimneys 11, 12 and 13 to a height above the normal level of pump fluid in the boiler compartments 15, 16 and 17. Each collar is mounted so that its lower edge rests on the bot-tom 14 of casing 10, the mounting means being adapted to permit limited vertical displacement of the collar relative to the chimney with which it is associated. In the preferred embodiment shown in the drawings, this is effected by means of a bolt 28 in each chimney extending into an aperture 29 in each collar, the apertures 29, 29 being substantially larger than the bolts 28, 28.

Thus, in the pump embodying the invention, the vapor chimneys are rigidly secured to each other while the collars are loosely mounted on the chimneys for vertical displacement relative to the chimneys. The entire unit of chimneys and collars can be inserted into or removed from the casing as a unit. The rigid mounting of the chimneys to each other ensures proper spacings in the jet nozzles at all times. The collars, being free to move can drop slightly below the ends of one or more of the chimneys when the bottom of the pump casing is not perfectly flat or when the chimneys are not all of exactly the right length to contact the bottom of the casing.

If, during service, the bottom of the casing becomes slightly warped, the collars automatically adjust for variations in the bottom of the casing.

I have found that the floating collars mini-mize objectionable seepage of pump fluid under the ends of the chimneys. The necessity for machining the bottom of the casing and the lower ends of the chimneys, or other costly and time-consuming expedients are obviated. The effectiveness of the collars in minimizing seep-age is reflected in better performance char-acteristics as shown by higher ultimate vacuums and increased pumping speeds.

While the invention has been described in con-siderable detail with reference to a preferred embodiment as shown in the drawings, it will be understood that variations and modifications can be effected within the spirit and scope of

the invention as described hereinabove and illus-trated in the drawings and as defined in the ap-pended claims.

I claim:

1. In a vertical diffusion pump, the combina-tion comprising a generally cylindrical casing, a bottom for said casing, a plurality of concentric vapor chimneys disposed in said casing and gen-erally concentric with said casing, said chimneys being secured together into a unitary chimney assembly, said chimneys being spaced from each other and from said casing and having the lower ends of said chimneys contiguous to the bottom of said casing and forming a plurality of generally concentric boiler compartments, each said chimney having a notch in the lower end of the chimney for permitting flow of pump fluid through said boiler compartments in series, a floating collar disposed around the lower end of each chimney in closely adjacent concentric re-lation with said chimney, said collars being sub-stantially out of frictional contact with said chimneys and having the lower circumferential edge of each said collar in contact with the bot-tom of said casing, said collars extending up-wardly along said chimneys to a height above the normal level of pump fluid in said boiler compartments, each said collar having a notch in the lower edge thereof in general alignment with the notch in the next adjacent chimney, each said collar having a wall opening therein in a localized upper zone of said collar, and pinning means secured to each said chimney and extending into the wall opening in the next adjacent collar, said pinning means being sub-stantially smaller than said wall opening for per-mitting limited vertical movement of said collars relative to said chimneys.

2. In a vertical diffusion pump, the combina-tion which comprises a generally cylindrical cas-ing, a bottom for said casing, a plurality of con-centric vapor chimneys disposed in said casing and generally concentric with said casing, said chimneys being arranged in spaced relation with each other and with said casing and having the lower ends of said chimneys contiguous to the bottom of said casing and forming a plurality of concentric boiler compartments within said cas-ing, each said chimney having an opening through the wall of said chimney contiguous to the lower end of said chimney and affording com-munication between said boiler compartments, a vertically displaceable floating collar disposed in closely adjacent and generally concentric rela-tion to the lower end of at least one of said chimneys, said collar having an aperture there-in in general alignment with the opening in said chimney closely adjacent to said collar, and mount-ing means securing said collar to said closely adjacent chimney and confining said collar to limited vertical displacement relative to said closely adjacent chimney.

3. In a vertical diffusion pump, the combina-tion comprising a generally cylindrical casing, a bottom for said casing, a plurality of concentric vapor chimneys disposed in said casing and gen-erally concentric with said casing, said chimneys being spaced from each other and from said casing and having the lower ends of said chimneys contiguous to the bottom of said casing and forming a plurality of concentric boiler compartments, each said chimney having an opening through the wall of said chimney contiguous to the lower end of said chimney for interconnecting said boiler compartments, a vertically displace-

able floating collar for the lower end of each said chimney, each said collar being disposed in closely adjacent and generally concentric relation to the lower end of one of said chimneys, said collars extending upwardly along said chimneys to a height greater than the normal level of pump fluid in said boiler compartments, each said collar having an aperture therein generally coinciding with the opening in the chimney closely adjacent to said collar, means securing 10 said collars to said chimneys, and means asso-

ciated with said collars for loosely engaging said securing means and confining said collars to limited vertical displacement relative to said chimneys.
